METHOD OF GENERATING STEAM.

1,031,721.

Specification of Letters Patent.

Patented July 9, 1912.

Application filed July 20, 1905. Serial No. 270,447.

To all whom it may concern:

Be it known that I, HENRY I. LEA, a citizen of the United States, and a resident of Pittsburgh, in the county of Allegheny and State of Pennsylvania, have invented a new and useful Improvement in Methods of Generating Steam, of which the following is a specification.

This invention relates to a method of generating steam.

The fact that steam is often utilized for various purposes besides the direct production of power has, to some extent, limited the introduction of gas producer plants and gas engines in the place of steam plants and steam engines.

The object of this invention is the production of a method of conserving the thermal energy of the exhaust gases of a producer plant and utilizing them in the production of steam.

In the single sheet of drawing accompanying this application, Figure 1 is a plan view of an assembled apparatus adapted to be utilized in performing the successive steps comprising the process embodied in this invention. Fig. 2 is a side elevation of the apparatus shown in Fig. 1. Fig. 3 is a sectional elevation of a detail of the apparatus.

While I do not wish to limit myself to the specific arrangement of the apparatus herein illustrated, a description of the drawings will be given in order that a clear understanding of the invention may be had.

A gas producer 3, which is provided with a suitable fuel feeding device 4, and which may be arranged to utilize the sensible heat of combustion in the gas generating chamber in generating the steam for the operating blast, is connected with a combined purifying apparatus 5, by a pipe 6. Connected to the pipe 6 is a valved pipe 7 which may be utilized as a stack in starting the producer. Leading from the purifier 5 is a gas main 8, to which is connected a branch pipe 9 provided with a suitable valve 10 supplying gas to the cylinders 11 of a gas engine 12. The exhaust passages of the gas engine are connected by a pipe 13 to a pipe 14, which is provided with a suitable valve 15. The pipe 14 is adapted to lead the exhaust gases from the engine cylinders into

a furnace 16 which is arranged to supply heat to a tubular boiler 17. The boiler 17 is provided with a suitable stack 18 and a safety valve 19. A pipe 20, which is provided with a valve 21 is also connected to the exhaust pipe 13 and when the valve 15 of the pipe 14 is closed, and the valve 21 is open, it is utilized for carrying the exhaust gases of the engine directly into the atmosphere.

The furnace 16 is provided with a bridge wall 22 adjacent to and beyond which the pipe 14 enters the furnace. A branch pipe 23 is connected to the main gas supply pipe 8 and introduces gas into the front of the furnace 16. A pipe 23 is connected to an automatic regulating valve 24 shown in section in Fig. 3. The valve 24 is provided with a valve chamber 25 to which is connected the pipe 23 and a pipe 26, the pipe 26 connecting with the furnace. A valve disk 31 is mounted on a suitable rod 28 and is adapted to vary the flow of gas through the chamber 25 (and therefore to the furnace), as the steam pressure in the steam boiler 17 varies. A spiral spring 29 surrounding the rod 28 and operating between the easing 30 of the valve, and a disk 27 mounted on the rod, tends to hold the valve disk 31 in such a position that a maximum flow of gas will be maintained through the chamber 25.

A piston 32, mounted on the rod 28 and operating in the cylinder 33, is arranged to vary the position of the valve disk 31 in accordance with the amount of steam pressure in the steam boiler 17. Leading from the steam boiler and entering the cylinder 33, is a steam pipe 34, so arranged that the pressure in the boiler will be transmitted to the piston 32 and tend to move the rod 28 in opposition to the spring 29.

The operation of the apparatus is as follows: The gas generated in the producer 3 is cleaned in the purifier 5 and is admitted to the cylinders 11 of the gas engine through the branch pipe 9; the amount of gas passing therethrough being controlled by the valve 10 or a suitably arranged governor valve, not shown. The exhaust from the engine cylinders 11 passes through the pipes 13 and 14 and enters the furnace 16, adjacent to the brick wall 22. For this arrange-

ment the valve 21 in the pipe 20 is closed and the valve 15 in the pipe 14 is open. In view of the fact that the exhaust gas leaving the engine cylinders carries with it as 5 sensible heat at least 30% of the total heat of the gas entering the engine, it is apparent that a large portion of this heat may be utilized in generating steam by passing the exhaust gases adjacent to the boiler 17 and 10 through the tubes with which it is provided. To provide for such demands of steam that cannot be supplied by the exhaust gases, gas from the producer is admitted through the front portion of the furnace 16, through 15 the pipe 26. Any suitable gas burner may be utilized within the furnace and since the gas enters under pressure it will mix at its entrance with the required amount of air for complete combustion. The flow of gas 20 through the pipe 23, as has been described, is controlled by the automatic valve 24 and varies inversely as the steam pressure in the boiler varies and by this arrangement it will be readily seen that a desired pressure, with 25 in close limits, can be maintained in the boiler. A suitable pilot light may be maintained adjacent to the point where the pipe 26 enters the furnace for igniting the varying flow of gas, from the valve 24, or the 30 disk 31 may be so arranged that it never entirely shuts off the flow of gas to the furnace. With the exhaust gases from the engine cylinder entering the furnace beyond the bridge wall, the combustion of the gases 35 entering through the pipe 26 is not impeded and as the gases resulting from this combustion approach the bridge wall 22, they mix with the exhaust gases from the engine. The economy of this apparatus may be still 40 further increased by conducting the water from the water jackets of the gas engine cylinders into the boiler.

Referring again to the figures: Cooling water is introduced into the water jackets 45 of the cylinders 11 through the pipe 35 and is discharged through the pipe 36, which connects with a hot well 37. The water from the hot well is pumped by a pump 38 into the boiler 17 through the pipe 39. The 50 water jackets in this case act as a feed water heater. By this arrangement the thermal value of the exhaust gases from the engine is taken advantage of and the thermal energy of the gases burned under the boiler 55 is efficiently utilized; and with such an apparatus the necessity of firing with coal or other solid fuel is overcome and the smoke nuisance is avoided and the expense of power, heating, etc. are materially decreased.

Having now described my invention what

I claim and desire to secure by Letters Patent is:

1. The combination with an internal combustion engine, of a heat conserving agent 65 adapted to convert heat energy into pressure energy, means for delivering the sensible heat of the exhaust gases from said engine to the heat conserving agent, a primary source of gas supply, heat delivery 70 means in-communication with the primary source of gas supply and the heat conserving agent, and means dependent upon the pressure generated within said agent for controlling the flow of gas through said 75 primary gas supply.

2. The combination with an internal combustion engine and a steam generator, of a source of heat supply for the steam generator comprising means for utilizing the 80 sensible heat of the exhaust gases from said internal combustion engine for heating the steam generator, a source of fuel supply leading to the steam generator and means dependent upon the steam pressure in said 85 steam generator for varying the amount of fuel from said source of fuel supply.

3. The combination with an internal combustion engine of a heat conserving agent adapted to convert heat energy into pressure 90 energy, a primary source of heat supply for the heat conserving agent comprising means for delivering the sensible heat of the exhaust gases from said engine to the heat conserving agent, a portion of the sensible 95 heat of the combustion taking place within said engine, a secondary source of supply leading to said agent and means dependent upon the pressure generator within said agent for controlling the secondary supply. 100

4. The combination with a source of gas supply, an internal combustion engine and a steam boiler, of means for connecting the exhaust of the internal combustion engine with the steam boiler so as to utilize the 105 sensible heat of the exhaust gases from said engine for generating steam in said boiler, a fuel supply independent of the exhaust from the internal combustion engine to supply heat to said boiler, and a valve provided 110 with a steam actuated plunger for controlling the delivery of fuel from said independent supply in accordance with the pressure generated in said boiler.

In testimony whereof, I have hereunto 115 subscribed my name this sixth day of July, 1905.

HENRY I. LEA.
